PIT-TYPE FURNACE

James M. Guthrie, Pittsburgh, Pa., assignor to
Loftus Engineering Corporation, Inc., Pittsburgh, Pa., a corporation of Maryland

Application October 8, 1946, Serial No. 701,951

3 Claims. (Cl. 263—15)

1

My invention relates to pit-type furnaces, particularly pit-type furnaces for heating or soaking ingots of steel or other metal, preparatory to forging, rolling, or the like, and the invention consists in certain new and useful improvements in the structure of such furnaces, whereby more efficient and more uniform heating of ingots or other articles may be obtained.

The art is familiar with a furnace known as the center-fired pit. As its name suggests, the pit is fired centrally through its bottom, or hearth, and the burning column of fuel streams vertically upward between the ingots of the charge supported on the pit bottom around the burner opening. The stream of flames impinges against the cover of the pit and spreads, umbrella like, over the charge, and then the flames and hot products of combustion descend from the "umbrella" in streams spaced radially outward from the burning column sustained by the central burner. Upon approaching the bottom of the pit the streams of hot waste gases find egress through outgo ports, which open through the pit side walls and communicate with heat-exchange means that are effective to salvage large quantities of residual heat from the gases and to transfer the heat to the combustion air which is fed to the burner. While many advantages have been recognized in the use of the center-fired pit, several disadvantages are to be noted. For example, the arrangement of the burner in the center of the pit floor results in a reduction in the ingot capacity of a pit of given size, the capacity of a pit being in general proportional to the area of the pit bottom which is available to receive ingots. Consequently, in order to obtain a specified pit capacity, it has been necessary to build a larger and more costly pit than would be the case if the entire bottom of the pit were available for the support of ingots. Additionally, it may be noted that the impingement of a stream of burning fuel against the pit cover is deleterious to the cover structure. Furthermore, when the burner in service fails to function properly, the entire pit must be shut down, it being understood that it is not uncommon for burners to require attention over prolonged periods of service.

In an application for United States Letters Patent, Serial No. 581,626, filed by me on March 8, 1945, now Patent No. 2,478,190, I have illustrated and described an ingot pit-type furnace which eliminates the objections to the center-fired pit, while obtaining or retaining its more important advantages. The pit of my said prior application is, as in the case of the center-fired

2

pit, designed with side walls which are relatively uniformly spaced with respect to a vertical center line arising from the center of the hearth of the pit, and thus constituted, is adapted to the mill floor plans and practice of a great many steel mills. However, in some cases, I have found it preferable to provide pits of relatively narrow elongate form, as viewed in plan, and in such elongate pits, I provide, as distinguished from the structure of my said copending application, a burner centrally in each end wall of the pit. These burners are located on the longitudinal vertical mid-plane of the pit; the burners direct their flames into a combustion space provided between the tops of the ingots charged in the pit and the cover of the pit, and the burners are so angled in their position that the flame, projected from the centrally located burners, are spread angularly substantially to cover the horizontal expanse of said combustion chamber; in furtherance of the latter effect the opposite side walls, and sometimes the opposite end walls too, are outwardly bowed as viewed in plan, this contouring of the walls assisting in the obtainment of a swirling and spreading of the flames delivered angularly into the combustion space above the ingots. In each of the end walls of the pit outlet ports are provided immediately above the coke breeze on the hearth, and these outlet ports in each end wall are arranged symmetrically of the longitudinal, vertical mid-plane of the pit chamber, whereby exact symmetry exists between the burners and outlet ports in each wall and between the burners and outbuilt ports in the two opposing end walls.

An embodiment of my present invention will be understood upon reference to the accompanying drawings in which:

Figure 1 is a fragmentary view in plan of a battery of pits, affording an exemplary embodiment of the invention;

Figure 2 is a view to larger scale, showing a pit partly in elevation and partly in section, the plane of section being indicated at II—II in Figure 1.

Referring to the drawings the pit furnace may be constructed as a unit having a single pit, or it may have a battery of pits, as indicated by the reference numeral 2 in Figure 1. The pits 2 are advantageously formed rectangular as viewed in plan, but their peripheral walls 3, 3 and 4, 4 may be internally curved outwardly to increase the durability and sturdiness of construction, and to promote more effective movement of burning fuel and products of combus-

tion within the pits. The furnace structure is built of refractory brickwork borne on suitable concrete foundations 5; the pit proper is supported upon a platform of steel channels 6, laid "toes down" on beams 7 that rest upon the foundation; and the structure is encased with steel plate, laterally reinforced and tied by means of conventional steel buck-stays and braces, the latter members being omitted from the drawings for the sake of clarity of illustration.

The hearth or bottom 8 of the pit includes one or more cleanout openings 9, which are normally filled with the coke breeze 10, or other suitable material which provides the floor upon which the ingots 11 stand, as shown in Figure 2. The pit is provided with a cover 12 that is temporarily removable to permit the ingots to be charged into the pit and removed. It will be observed that the entire area of the bottom of the pit is available for the support of ingots, with the ingots arranged and spaced properly in accordance with ingot size and shape.

The pit chamber, it will be seen, is of greater depth than the height of the ingots supported on the hearth 8, providing a combustion space between the tops of the ingots and the cover 12.

Each pit is provided with a particularly effective organization of burners, together with an effective arrangement of waste gas ports for removing the hot waste gases or products of combustion from the pit chamber, all to the end that a more effective distribution of heating effect may be established and maintained throughout all portions of the pit chamber, not only when the pit is fired at a maximum heating capacity but also when the burners are turned down for soaking or "holding" the charge of ingots.

More particularly, I provide a burner 13 in each of the opposite end walls of the pit chamber. These burners 13 are aligned with the longitudinal center line of the chamber, and are located to direct burning columns of fuel and air into the combustion space above the ingots in the chamber. The burners may be canted upwardly, as appears in Figure 2, to give a "lift" to the burning columns entering the combustion space above the ingots. It is important to note that the burners are inclined or extend angularly, as viewed in a horizontal plane above the pit, and by virtue of this burner arrangement the burning column delivered by one burner into the combustion space above the ingots is directed angularly to one side of the longitudinal center line of the chamber, while the column delivered by the opposite burner is directed angularly to the other side of said center line. The two columns, thus entering the combustion space in substantial parallelism, spread and provide an exceedingly effective coverage of the horizontal expanse of the pit chamber, and it may be noted that the outwardly curved internal surfaces of the chamber walls cooperate with the angled columns of flames and hot gases to provide the desired coverage and uniform heat distribution in the pit chamber.

Below the burners, outlet ports 14 open through the end walls 3, 3 and lead into heat-exchange units 15 for preheating the combustion air that is fed through a duct system 16 to the burners. The arrangement of the outlet ports is such that the drafting of waste gases from immediately above the bottom of the pit chamber is substantially symmetrical with respect to the firing effect of the burners above the ports. While a single wide outlet port, or row of three or more ports,

may be arranged in each wall 3 to give this desired effect, I advantageously provide two outlet ports for each burner, such ports being arranged substantially directly below the associate burner, one on each side of the longitudinal vertical mid-plane of the chamber.

The effect of the described burner and outgo port organization is to insure at all customary rates of firing a uniform distribution of heat throughout the pit chamber and its charge. The burners 13 are luminous flame burners, and, as the art well knows, a luminous flame burner is one whose flame contains unburned particles or molecules of fuel. In the travel of the fuel from the burner these particles are progressively heated to incandescence and burned, so that the heat release of the flame is distributed over a long path of flame travel, rather than being concentrated at a point located a relatively short interval from the burner. Accordingly, my arrangement of angled long luminous flames in a combustion space above the tops of the ingots does not mean that combustion is completed above the tops of the ingots. On the contrary, burning tongues of flame are drawn downward between the ingots as well as between the ingots and the pit walls, such movement of the flames being promoted by the pressure created by the injected burning fuel and air at the top of the pit, plus the suction of the draft acting through the symmetrically arranged outlet ports. A beneficial prolongation and distribution of combustion, and a thoroughly disseminated movement of the hot waste gases, are provided in the pit at all customary firing rates.

The waste gases emerging from the outlet ports 14 enter recuperators 15 at the opposite ends of the pit structure. Various types of recuperators may be adapted for the purpose of salvaging heat from the waste products of combustion within the pit, and imparting a high degree of preheat to the air for the combustion of fuel. However, I prefer recuperators of the construction illustrated and described in my copending application, Serial No. 581,626, filed March 8, 1945, and it is needless to an understanding of my present invention to consider in detail the structure of such recuperators. Suffice it herein to say that the waste gases are delivered from the outlet ports 14 through the recuperators to a stack or other vent, while the air for combustion is led through the recuperators and ducts 16 to the burners 13. The preheated air delivered by ducts 16 to the burners is subject to the control of valves 28. The fuel is delivered to the burners through nozzles 29, each of which includes a control valve, and, by the adjustment of such fuel valves and the air control valves, the desired rate of combustion may be established in each pit chamber. It goes without saying that conventional proportioning mechanism for air-fuel ratio control, and for temperature and pressure control in each pit chamber may be provided.

Within the terms of the appended claims certain variations and modifications of the structure described may be practiced without departing from the spirit of the invention.

I claim as my invention:

1. In a pit-type ingot furnace of general rectangular form in plan, having refractory side and end walls, a hearth for supporting ingots on end, a movable cover, means for firing the furnace including piping for fuel and combustion air, a flue system for leading the hot products of combustion from the furnace, and heat-exchange

means arranged with said flue system for pre-heating said combustion air; the improvements herein described wherein said furnace includes a combustion chamber extending between the tops of said ingots and said cover, said firing means comprising two burners opening severally through the end walls of said furnace at points substantially midway between the furnace side walls, said burners being angled relatively to said side walls and inclined upwardly, whereby the burning column delivered by one burner is directed upwardly and toward one of said side walls and the burning column delivered by the other burner is directed upwardly and toward the other side wall, said columns expanding laterally to provide a turbulent body of flames and hot gases distributed over the horizontal expanse of said combustion chamber above the ingots in the furnace, and outlet ports opening through the furnace walls into said flue system at points located near said hearth, said ports being substantially symmetrical with respect to said burners as viewed in plan and being productive of a distributed flow of the flames of hot gases downwardly from said combustion chamber and over and around the bodies of the ingots in said furnace.

2. In a pit-type ingot furnace of general rectangular form in plan, having refractory side and end walls, a hearth for supporting ingots on end, a movable cover, two burners for delivering burning columns of fuel and air into the furnace, piping for delivering fuel and combustion air to said burners, a flue system for leading the hot products of combustion from the furnace, and heat-exchange means arranged with said flue system for preheating said combustion air; the improvements herein described wherein said furnace includes a combustion chamber extending between the tops of said ingots and said cover, said two burners opening severally through the end walls of said furnace at points substantially midway between the furnace side walls, the side walls of said furnace being outwardly bowed, as viewed in plan, said burners being angled relatively to said side walls, whereby the burning column delivered by one burner is directed toward one of said outwardly bowed side walls and the column delivered by the other burner is directed toward the other said side wall, said columns expanding laterally to provide a turbulent body of flames and hot gases distributed over the horizontal expanse of said combustion chamber above the ingots in the furnace, and outlet ports opening through the furnace walls into said flue system at points located near said hearth, said ports being substantially symmetrical with respect to said burners as viewed in plan and

being productive of a distributed flow of the flames of hot gases downwardly from said combustion chamber and over and around the bodies of the ingots in said furnace.

- 5 3. In a pit-type ingot furnace of general rectangular form in plan, having refractory side and end walls, a hearth for supporting ingots on end, a movable cover, two burners for delivering burning columns of fuel and air into the furnace, piping for delivering fuel and combustion air to said burners, a flue system for leading the hot products of combustion from the furnace, and heat-exchange means arranged with said flue system for preheating said combustion air; the improvements herein described wherein said furnace includes a combustion chamber extending between the tops of said ingots and said cover, said two burners opening severally through the end walls of said furnace at points substantially midway between the furnace side walls, said burners being angled relatively to said side walls and inclined upwardly, whereby the burning column delivered by one burner is directed upwardly and toward one of said side walls and the column delivered by the other burner is directed upwardly and toward the other side wall, said columns expanding laterally to provide a turbulent body of flames and hot gases distributed over the horizontal expanse of said combustion chamber above the ingots in the furnace, and outlet ports opening through the furnace walls into said flue system at points located near said hearth, said ports being substantially symmetrical with respect to said burners as viewed in plan and being productive of a distributed flow of the flames of hot gases downwardly from said combustion chamber and over and around the bodies of the ingots in said furnace.
